(57) CLAIM

The ornamental design for a shower sandal, as shown and described.

DESCRIPTION

FIG. 1 is a top plan view of the left shower sandal showing the new design;

FIG. 2 is a bottom plan view thereof;

FIG. 3 is a medial side view thereof;

FIG. 4 is a rear, top, lateral side, perspective view thereof; and,

FIG. 5 is a front, top, lateral side, and perspective view thereof.
